APPARATUS FOR CEMENTING WELLS

Domer Scaramucci, Oklahoma City, Okla., assignor to Oil Equipment Engineering Corporation, Oklahoma City, Okla., a corporation of Oklahoma

Application August 18, 1939, Serial No. 290,891

7 Claims. (Cl. 166—1)

The present invention relates to improvement in apparatus for cementing wells, and pertains particularly to the process of cementing in which a cement slurry is forced down a well casing between two plugs which separate it from the well fluid.

The fundamental purpose is to provide apparatus which will enable an operator accurately to retain a predetermined volume of slurry in the well casing above the shoe. It is customary in cementing casing to retain the upper part of the cement batch within the shoe, because that part is usually soft and contaminated and to insure proper cementing at the lower end of the casing. When the well is completed, the part remaining in the casing can be drilled out easily.

Several methods have been used hitherto for this purpose, but each is subject to some important objection. In one of these, a special baffle is installed at the proper point in a casing string as it is made up to go into the well and the baffle is used in positioning the top plug. Another method employs a measuring line to follow the top plug in its downward travel. The latter method is uncertain where applied to a long string of casing containing heavy drilling fluid, which makes it difficult to detect the plug. The invention herein to be described requires no special casing attachment, or does it need the continuous attention of the operator.

It is a principal object of this invention to provide means for positioning the top cementing plug above the foot of the casing, whereby a definite amount of cement may be retained in the casing.

A further and specific object is the provision of simple and efficient means which are associated with the top and bottom cementing plugs for retaining a predetermined amount of the cement batch within the lower end of the casing.

A more specific object which this invention comprehends is the inclusion of a coloring medium an appreciable distance above the foot of the casing string which will be released before the drill passes through the casing shoe.

The two-plug cementing procedure of this invention utilizes a valve member which is maintained within the cement slurry a predetermined distance below the top plug to close the opening through the bottom cementing plug after a major portion of the cement slurry has been discharged through that plug and out into the annular space between the casing and the well bore.

That is to say, the two plugs spaced by the cement slurry are forced down the well casing until the bottom plug reaches the foot of the casing and discharges a large portion of the cement slurry, whereupon its opening will be closed by the valve member and a predetermined volume of inferior or contaminated slurry will be unable to escape. The coloring medium which has been mentioned may form a part of the valve member and will be liberated by the drill as it goes through the bottom plug. In this alternative or modified embodiment, it is preferable to use an appreciably elongated bottom plug so that the coloring medium may be carried to the surface by the drilling fluid before the drill travels below the casing.

The preceding and other features and advantages of the invention will be better understood and appreciated from a reading of the following detailed description of a specific embodiment, and one modification, in connection with the accompanying drawing, in which—

Fig. 1 represents a side elevation, partly in longitudinal section, of an oil well having a casing inserted therein and containing two cementing plugs spaced by a batch of cement slurry;

Fig. 2 is a longitudinal section similar to Fig. 1, with the exception that the plugs and cement have moved to a position farther down the well casing;

Fig. 3 shows an enlarged vertical cross-section of a valve member which cooperates with the cementing plugs of Figs. 1 and 2;

Fig. 4 is a fragmentary vertical section of the well and casing, similar to Fig. 2, but illustrating modified forms of valve member and bottom cementing plug;

Fig. 5 is an enlarged vertical section of the valve member of Fig. 4; and

Fig. 6 illustrates by means of a vertical section a further embodiment of the valve member.

Referring to Fig. 1, a well bore WB has inserted therein a conventional string of well casing 10 which is of smaller diameter than the well bore and with which it defines an annular space. A casing head 12 adapted for the well cementing operation is secured in place at the upper end of the casing. At its lower end, the casing 10 is provided with a combination guide 50 and float shoe, the valve means 16 of which is arranged to permit a cement slurry CS to be discharged downwardly therethrough and fill the outer space between the well casing and the lower end portion of the well bore WB, in the manner shown in Fig. 2.

Attention is now directed to a bottom cementing plug 18 and a top cementing plug 20 which are spaced by the cement slurry CS and separate it from the drilling or well fluid WF within the casing 10; both plugs will ordinarily be formed from wood. The bottom cementing plug 18 is provided with an opening, illustrated as a bore or passageway 22, which is closed by a rupturable diaphragm and sealing member 24, of rubber or other suitable material. Fig. 1 shows the diaphragm 24 in an unruptured condition and Fig. 2 indicates the ruptured condition which is produced by the continued application of downward pressure after the bottom plug 18 is stopped by the casing shoe 14.

A valve member or ball 26 is maintained within the cement slurry CS at substantially the same predetermined distance below the uppermost or top cementing plug 20 by suspending it from the bottom side of the latter with a flexible line 28 of manila rope or other suitable material. A connecting eye 30 of brass is secured to the valve member 26 to provide convenient means for attaching the suspending means or line 28. While the ball valve member 26 may be formed from any suitable material which is sufficiently frangible and has a greater specific gravity than the cement slurry, aluminum is preferred.

By means of the measured length of line 28, it is possible for the operator to predetermine and control the volume of the cement slurry which will be trapped within the casing 10 after the valve member 26 has moved relatively into sealing engagement with the upper end of the bore 22 of the bottom plug 18 (Fig. 2). As illustrated, the valve or closing member 26 is suspended in an aligned position with respect to said plug bore 22 and is of a size and shape to seal the bore 22 effectively when the discharge of cement from the bottom of the casing causes it to move into closed position. It will be understood that the apparatus which has been described in detail requires no further attention from the operator after the top plug 20, carrying the valve member 26 on its lower end, has been placed within the casing 10 on top of the batch of cement slurry. The operator is then able to force the cement down the casing at maximum speed by means of hydraulic pressure applied to the upper end of the top plug 20, until the discharge of cement through the bottom plug 18 and shoe 14 has been stopped abruptly by the closing action of the valve member 26.

Figs. 4, 5 and 6 illustrate the use of modified forms of valve members which include the coloring medium. In one form, a hollow spherical valve member 260 of cast aluminum is filled with a coloring agent 261. This valve member 260 is suspended from the line 28 by a connecting eye 300 in the manner previously described.

In order to provide a greater amount of the coloring medium, a hollow cylindrical form of valve member 2600 containing a coloring agent 3000 may be utilized. This valve member 2600 will also be made of a suitable drillable material such as aluminum. The upper end of the valve member 2600 is provided with a connecting eye 2620 and it is shaped at its lower end so as to seal the bore of the bottom cementing plug.

A wide variety of coloring mediums may be used in practicing this invention. A definite color indication and an ability to rise with the drilling fluid are the fundamental requisites. Therefore, the coloring medium (261 or 2610) may be solid powder such as a red oxide of iron, or a liquid

dye which will give the drilling fluid a distinctive color, e. g., a chromate solution is quite suitable.

When the valve member is provided with a coloring medium, it is desirable to utilize an elongated form of bottom cementing plug 180 having a longitudinal bore 220 and rupturable diaphragm 240 over the bore. With a plug of this length, an intermediate sealing washer 182 of split construction is provided. The elongated plug 180 serves to position the coloring supply well above the shoe (14) so that the circulating fluid in which the coloring floats or is conveyed will have ample time to return to the surface before the drill has penetrated below the casing shoe.

The operation of the apparatus has been fully described in the preceding paragraphs. Notable improvements in the cementing of wells are effected by the practice of the present invention. Instead of leaving an indeterminate amount of cement slurry within the casing, with a generous allowance that there shall be too much rather than too little, the exact volume to be retained is predetermined before the pumping of the cement is commenced. After this determination is made by spacing the member which closes the passage of the bottom plug a fixed distance below the top plug, the operation may proceed with maximum speed without the necessity of sounding for the top plug, measuring the volume of pumped fluid, or attaching some special casing device such as a baffle.

Those familiar with this art will understand that the foregoing descriptions of the preferred forms of apparatus are for purposes of illustration, and that various changes and modifications can be made which will come within the scope and spirit of the appended claims.

What I claim as new and desire to secure by Letters Patent of the United States is:

1. Apparatus for use in cementing a well, comprising a well casing, a pair of cementing plugs adapted to be inserted in said casing at the lower and upper ends respectively of a body of cement slurry, a valve member between the plugs, suspending means for maintaining the valve member substantially the same distance below the top plug, and shoe means positioned at the bottom end of the casing for engagement with the bottom plug to stop its downward movement, said bottom plug having a through passageway arranged to be closed by the valve member when sufficient cement has escaped from the casing to permit the valve member to move into closing engagement.

2. Apparatus for use in cementing a well, comprising a well casing, a pair of cementing plugs adapted to be inserted in said casing at the lower and upper ends respectively of a body of cement slurry, a ball valve member having a greater specific gravity than the slurry disposed between the plugs, suspending means for maintaining the valve member substantially the same distance below the top plug, and shoe means at the bottom end of the casing and positioned for engagement with the bottom plug to stop its downward movement, said bottom plug having a passageway arranged to be closed by the valve member when sufficient cement slurry has escaped from the casing to permit the valve member to move into closing engagement.

3. The combination which comprises a well casing having a shoe at its lower end; a top cementing plug and a bottom cementing plug adapted to be inserted in the casing at the top and bottom respectively of a body of cement

slurry, said bottom plug having a longitudinal bore and a rupturable diaphragm closing its bore; a frangible ball valve which will sink in a cement slurry; and a flexible line connected to the top plug and ball valve for suspending the latter a fixed distance below the top of the body of slurry, the bore of the bottom plug and the ball valve being in alignment so that the bore will be closed by the valve when rupture of the diaphragm and discharge of the slurry permit them to engage.

4. Apparatus for use in cementing a well, comprising, a well casing, a pair of cementing plugs adapted to be inserted in said casing at the lower and upper ends respectively of a body of cement slurry, a frangible valve member containing coloring matter disposed between the plugs, a line connected to the top plug and valve member for maintaining the valve member a fixed distance below said top plug, and shoe means at the bottom end of the casing and positioned for engagement with the bottom plug to stop its downward movement, said bottom plug having a bore arranged to be closed by the valve member when sufficient cement slurry has escaped from the casing to permit the valve member to move into closing engagement, and the coloring matter being releasable as the cement in the casing is drilled.

5. In combination with a well casing, a top cementing plug, a valve member, means for suspending the valve member substantially the same distance below the top plug, and a bottom cementing plug having a through passageway arranged to be closed by the valve member, when engaged thereby.

6. In combination with a well casing, a top cementing plug, a frangible valve member including a color indicator, means for suspending the valve member substantially the same distance below the top plug, and a relatively long bottom cementing plug having a through passageway arranged to be closed at its upper end by the valve member when engaged thereby, so that the color indicator may be released by drilling before the drill reaches the lower end of the bottom plug.

7. In combination with a well casing, a top cementing plug, a valve member which includes a coloring agent below said top plug, means for suspending the valve member substantially the same distance below the top plug, and a bottom cementing plug having a longitudinal bore arranged to be closed at its upper end by the valve member when engaged thereby.
